UNITED STATES PATENT OFFICE.

HERBERT C. BLISS, OF ATTLEBORO, MASSACHUSETTS.

DESIGN FOR A TUBULAR STOCK FOR JEWELRY OR SIMILAR ARTICLES.

42,411.

Specification for Design.

Patented Apr. 23, 1912.

Application filed March 10, 1911. Serial No. 613,668. Term of patent 7 years.

To all whom it may concern:

Be it known that I, HERBERT C. BLISS, a citizen of the United States of America, residing at Attleboro, in the county of Bristol and State of Massachusetts, have invented a new, original, and ornamental Design for a Tubular Stock for Jewelry or Similar Articles, of which the following is a specification.

Figure 1 is a perspective view of a piece of tubular stock showing my new design, and Fig. 2 is an enlarged view in end elevation.

The leading feature of my design resides in the stepped side edges of the stock which converge inwardly and join with the top. The said top is slightly convex on its outer face while the base which is of materially greater width than the top has its inner and

outer faces in parallel planes with curved longitudinal edges that merge into the stepped edges of the stock. The steps of these edges are of decreasing width from the inner to the outer step, and the outer faces thereof are convexed in substantially the same degree as the convexed outer face of the top.

I claim:

The ornamental design for tubular stock for jewelry or similar articles as shown and described.

In testimony whereof I have affixed my signature in presence of two witnesses.

HERBERT C. BLISS.

Witnesses:

ERNEST M. BLISS,
WILLIS H. STREETER.
